UNITED STATES PATENT OFFICE

GEORGE A. SPILLER AND GEORGE T. JOHNSON, OF COLUMBUS, OHIO, ASSIGNORS TO THE
BUCKEYE STEEL CASTINGS COMPANY, OF COLUMBUS, OHIO

RAILROAD CAR END

Application filed April 3, 1929. Serial No. 352,202.

This invention relates to railroad car ends, and especially to a "fixed end" for gondola type cars. More specifically, the invention pertains to a typical gondola car having "fixed ends", that is, there is no door in the 5 end of the car, but a fixed wall, which is usually constructed of rolled sheets and shapes, riveted together.

There are many objections to the built-up 10 type of car end. For example, it soon becomes considerably bulged, and otherwise distorted, due principally to end-wise shifting of loose lading, and to careless handling 15 of unloading crane buckets, so as to demand repair or replacement. Furthermore, the sheet portion or web is relatively thin, being only about one-quarter or five-sixteenths 20 inch thick, and when the car end is bulged, the rivet holes tear, or the rivets loosen, and such loosening of the connections destroys its strength.

In addition, the distortion of the car end is transmitted to the brake staff, which is attached thereto, and interferes with its safe 25 and efficient operation.

H-shaped beams, are often placed horizontally across the end of the car at intermediate 30 levels in order to stiffen the car end, but such beams bend outward and they also collect dirt and water, so that their use is objectionable.

The primary object of the present invention is to provide a car end which will eliminate such disadvantages, and we have found 35 it possible to design such a car end providing it is of a one-piece or cast metal construction.

Other objects of the invention are to provide 40 a car end of this character that is properly reinforced to take care of the various strains to which it is subjected; that may readily receive and support stakes employed 45 in increasing the height of the car body; that is provided internally with an integral inside ladder; that may be furnished at its lower 50 corners with push pole pockets, chain pull holes, and corrugated jacking pads; and that is further provided with means to permit of the air brake pressure retaining valve being mounted on or removed from the exterior of 55 the car end, even while the car is fully loaded.

It is customary to "heap up" coal and other bulk material with which cars are loaded. For each material, there is a certain "angle of repose" above which it cannot be heaped. Due to starting, stopping and buffing of 60 trains, the top material at the ends of the cars is disturbed, and the material rolls off over the ends of the car, unless it is provided with gabled ends, which are higher than the car side. The idea of using gabled ends is not 65 novel with us, but the means of constructing this gable or "heaped end" in connection with a cast car end is, we believe, new, and it is therefore another object of the invention to furnish a novel cast metal car end in which 70 the gable is integral with the main portion of the end.

A further object is to provide a cast metal car end, including an integral chain pull 75 loop for the emergency chaining of cars together in case a coupler fails to function. This loop will preferably be located just above the lower horizontal reinforcing member 80 of the car end, and will be integrally united therewith by a heavy vertical rib on 75 the inside of the car end.

With the foregoing objects outlined and with other objects in view which will appear as the description proceeds, our invention 85 consists in the novel features hereinafter described in detail, illustrated in the accompanying drawings, and more particularly pointed out in the appended claims.

Referring to the drawings,

Fig. 1 is an elevation of the improved car 85 end, viewed from its outer side.

Fig. 2 is a top plan view of the same.

Fig. 3 is a vertical sectional view on the line 3—3 of Fig. 1.

Fig. 4 is a similar view of a detail on the 90 line 4—4 of Fig. 1.

Fig. 5 is a horizontal sectional view of a detail of a modification.

Figs. 6 and 7 are respectively, a front elevation and a vertical sectional view of this 95 portion of the modification.

Fig. 8 is a front elevation of a simplified embodiment of the invention.

Fig. 9 is a top plan view of the structure 100 shown in Fig. 8.

Fig. 10 is a vertical sectional view, taken on the line 10—10 of Fig. 8.

Figs. 11 and 12 are respectively, a front elevation and a vertical sectional view of an alternate form of bracket to which the brake control may be connected from the exterior of the car.

Fig. 13 is an elevation of the upper portion only of the car end shown in Figs. 1 to 3 inclusive, with our improved gable extension.

Fig. 14 is a top plan view of the car end, shown in Fig. 13.

Figs. 15 and 16 are vertical sectional views taken respectively on lines 15—15 and 16—16 of Fig. 13.

Fig. 17 is an elevation of the lower portion of the car end shown in Figs. 8 to 10 inclusive, with our improved chain pull loop, which is integral therewith.

Fig. 18 is a vertical sectional view on the line 18—18 of Fig. 17.

Fig. 19 is a horizontal sectional view of a detail on the line 19—19 of Fig. 17.

In the embodiment of the invention illustrated in Figs. 1 to 5 inclusive, 15 designates the metal casting forming our one-piece fixed car end. Of course, in making such casting, the various portions thereof, will be made of requisite thickness to withstand without distortion or breakage, the severe strains to which such structures are subjected.

The web 16 of the structure is provided at its upper end with an outwardly extending flange 17 which is interrupted at a plurality of spaced points by stake pockets 18 which are reinforced at their lower ends by flanges or heads 19 that have their ends merging into the web 16. At the places where the pockets are located, the flange 17 is extended or thickened, as shown at 22 or 23, so as to provide a rugged construction at these places.

Inwardly extending flanges 23 are provided along the side edges of the web, and they merge near their lower ends into a horizontal bottom flange 24; the flanges 23 and 24 being provided with apertures 25 to receive the rivets employed in fastening the car end to the sides and bottom or floor of the car.

From Figs. 1 and 3, it may be seen that the ends 26 of the flange 17 are arranged at angles to the main portion of this flange, and they project inwardly over the flanges 23, and those flanges are notched at their upper ends, (see 27), to receive the top or bulb angles 28 that extend along the sides of the car body (one of said angles is shown in Fig. 1). The extensions 26 are apertured at 29 for the purpose of riveting the same to the bulb angles at the sides of the car.

Reverting to Fig. 1, it may be seen that the flange 17 is also reinforced by an apron 30 which is equal in length to the car end, and is gradually tapered upwardly from its central portion to its ends. This makes the apron deeper or of greater strength where the

latter is required most, that is, at the medial portion of the car end. It will also be noted that this apron merges into the stake pockets, so that the integral parts at the top of the car end furnish the requisite strength and durability.

Below the flange 17, the web is reinforced by a shelf 31 which is strengthened by an apron 32. The ends of the apron and the inner portion of the shelf merge into the web, and we prefer to make this apron also of greater depth at its medial portion, to provide the greatest reinforcement where it is most needed. Lugs 33 are arranged on the shelf, and are reinforced by ribs 34, and these lugs are placed to receive the lower ends of stakes inserted through the stake pockets, so as to prevent such stakes from shifting lengthwise of the shelf.

Between the flange 17 and the shelf, we place an internally projecting pocket 35, and the portion of the web covered by this pocket is provided with an elongated opening 36 and vertically disposed slots 37. This construction allows the brake pressure retaining valve to be secured to the car end from the exterior of the latter.

Above and below the shelf, the web is provided with foot pockets 38 which form an inside ladder for the car end.

Push pole pockets 39 are provided on the lower corners of the web, and as these corners are reinforced by the bottom and side flanges, they are capable of withstanding the forces to which they are subjected.

We also extend the web downwardly at these corners, to provide extensions 39^a which have side flanges 40 forming extensions of the side flanges of the webs. Each of these extensions is beaded at 42, and such bead extends from the bottom flange to a jacking pad 43 that is provided with a corrugated lower surface. The construction of the extensions admirably fits the same to receive holes 44 adapted for the reception of emergency pull chains, and the edge of the hole is beaded or thickened as shown at 45, and this bead is joined by a thickened neck 46 to the bead 42.

We also prefer to join the beaded portion at the edges of the holes to the bottom and side flanges by thickened parts or necks 49.

Instead of arranging the stake lugs on the shelf, as shown in Figs. 1 to 3 inclusive, we may, in cases where the shelf may be made wider, provide the shelf with three lugs 50 for each stake, as shown in Figs. 5 to 7 inclusive. In such construction, the lugs will confine the stakes from movement in any direction, and the outermost one of each set of lugs may be reinforced by a rib 51, which merges into the skirt 32 of the shelf.

In the modification shown in Figs. 8 to 10 inclusive, the construction has been simplified for use in cases where the stake pockets, the

chain pull holes or the roughened jacking pads are not desired. In this form of the invention, the top flange 17^a is unobstructed or unbroken from end to end, and the shelf 31^a has a smooth upper surface owing to the elimination of the stake retaining lugs.

As a further distinction, the retaining valve bracket 35^a consists of a short shelf 35^b, provided with an apron 35^c in which the vertical slots 37^a are formed. Both the shelf and apron are reinforced by a rib 35^d which is integral with the web 16^a, the shelf and apron.

Instead of the retaining valve brackets shown in Figs. 1 and 8, we may employ the alternate construction which we have designed, that is illustrated in Figs. 11 and 12. In this form the web 16^b of the car end is provided with an integral open ended trough-shaped member 35^e, which has vertical bolt receiving slots 35^f.

In the modification shown in Figs. 8 to 10 inclusive, the push pole pockets 39^b are positioned on the extensions 39^c, instead of in the corners at the lower end of the web.

As a resumé of some of the advantages of the invention, we may state that the top corner connection 26 provides a substantial advantage over the intricate details in built-up construction, as to the number of parts and ease of riveting. Its greater thickness resists corrosion, fewer rivets are exposed, and a stiffer corner is made. The same remarks also apply to the side flanges 23.

It may also be noted that the car end as a whole is stiffened by three integral members 17, 31, and 24 which are of sufficient section to prevent any appreciable bulging. The flange 24 also stiffens the corners where the push pole or chain is applied, and seals the car floor and under-frame at points where corrosion is most likely to occur.

The intermediate reinforcement 31 effectively stiffens the central portion of the car end, and as it is tapered from the center toward the ends, the reinforcement is distributed to most advantageous points. Furthermore, this reinforcement presents smooth rounded surfaces which provide a factor of safety and resists corrosion. The shelf also serves to hold the lower ends of the stakes, when such stakes are used.

Top member 17 has three functions; it stiffens the upper part against the bulging effect of the lading, provides a wide smooth "top rail" for resisting blows and for making connection with the bulb angle along the sides of the car, and make possible the inclusion of integral end stake pockets 18.

It is well known that in gondola type cars, there is an air pressure retaining valve near the brake staff, and that this valve is part of the air brake system. Such valve is usually attached to the car end by two bolts which extend through holes in the sheet metal form-

ing part of the car end. The heads of the bolts are exposed to the corrosive action of the elements, and the lading, and they cannot be replaced unless the car be at least partially unloaded, owing to the fact that when the car is loaded, the load will cover the inner ends of the bolts. The structures 35, 35^a and 35^e which we have designed, will remove the above mentioned disadvantages, as the inner ends of the bolts will be protected from the elements and from the lading, and the bolts may be manipulated or replaced from the exterior of the car. The vertical slots are used in these structures instead of round holes, in order to facilitate attachment of the valve.

It may also be stated that in a train of empty gondola cars, a trainman traveling from car to car, must either jump down on the floor and climb out of each car, or walk the bulb angle along the upper edge of the side of the car, unless the cars are provided with inside ladders. Our design of integral inside steps 38 demonstrates how well such details can be taken care of in integral construction. There is a large and comfortable bearing area for the trainman's foot. No portion of the step projects appreciably into the interior of the car, to become a nuisance or a hazard. These inside steps are also located beside the outside ladder (not shown) and are staggered, for greater convenience.

The push pole pockets 39 are easily formed in the integral construction, and partly because of their location, will require no reinforcement.

By means of the chain pull holes 44, the cars may be chained together temporarily in case a coupler fails to function.

The jacking pads 43 are used when trucks must be removed from under the car body, and due to the corrugations on these pads, slippage between the car body and the head of the jack will be prevented.

We may also mention that the integral construction which we have designed, allows metal to be removed from locations where it is not useful, and placed at points where needed. It presents smooth rounded surfaces, and fewer joints, reducing corrosion and accidents to a minimum, and eliminating points of stress concentration. It saves the work incident to collecting and fitting many separate pieces. The number of rivets, particularly is reduced, and the integral car end will dispense with a large number of parts, and effect a very substantial saving in weight.

As heretofore stated, it is common practice to "heap up" coal or the like with which cars are loaded, and for each material there is a certain "angle of repose" above which it cannot be heaped. Due to starting, stopping and buffing of trains, the material at the ends of the car is distributed, and it rolls off over the ends of the car, unless such ends are provided with gable extensions which are higher

than the car sides. Such extensions may be admirably worked into cast metal car ends in accordance with our invention. For example, the form of the invention shown in Figs. 1 to 3 inclusive may be provided with a gable extension, as illustrated in Figs. 18 to 16 inclusive. In this form of the invention, the main web 16^b is extended upwardly to provide a gable web 16^c of gradually increasing height from its ends to its central portion, and the upper edge of the gable web is provided with a reinforcing bead 16^d throughout its whole length, both for the reasons of safety and strength. This bead is constructed with a comparatively large radius fillet 16^e on the under side, so that unloading buckets, hooks, etc., will not catch on it. The web 16^c is also reinforced by four ribs or braces 16^f which are continuations of the walls of the stake pockets 18^b. It will be noted that the two central ribs 16^f diverge upwardly, in order to receive their share of the load, and to reinforce the gable vertically against possible blows. As shown in Fig. 15, the central ribs are also of gradually decreasing width from the flange 17^b to the upper edge of the gable extension.

While we have shown the gable extension feature as applied to a car end of the type shown in Figs. 1 to 3 inclusive, it is manifest that this feature may also be incorporated in a structure of the type shown in Figs. 8 to 10 inclusive, or in any other integral car end falling within the spirit of our invention.

Instead of using the chain holes 44, we may provide our car end with a chain pull loop 44^b, as shown in Figs. 17 to 19 inclusive. Such loop may be used for emergency chaining of cars together in case a coupler fails to function. It will be noted that this loop is located just above the lower horizontal reinforcing flange 24^b, and is integrally united therewith by a heavy vertical rib 44^c which is arranged on the inside of the car end. This is a most advantageous position for strength, and particularly so since the loop is located at or near the longitudinal center line X of the car (Fig. 17). This pulling loop may be placed at the exact center line of the car end when such a position will not interfere with the particular coupler operating device used.

While we have disclosed what we now consider preferred embodiments of the invention in such manner that the construction and advantages may be readily understood by those skilled in the art, we are aware that various changes may be made in the details disclosed, without departing from the spirit of the invention as expressed in the claims.

Having fully described our invention what we claim as new and desire to secure by Letters Patent, is:—

1. A one-piece metallic car end provided with reinforcing flanges, said flanges being

integral with the car end and with each other where they meet.

2. A one-piece metallic car end provided with top, bottom and side reinforcing flanges, said bottom flange being integrally united at its ends with the lower ends of the side flanges.

3. A one-piece metallic car end, provided with reinforcing flanges, one of which projects from one side thereof, and another of which projects from the opposite side thereof, said flanges being integrally united at their ends.

4. A one-piece metallic car end, provided at its upper edge with a reinforcing flange having a depending strengthening apron, and reinforcing means merging into the flange and said apron.

5. A one-piece metallic car end provided at its upper edge with a reinforcing flange having a depending strengthening apron, said apron tapering upwardly from its medial portion toward the ends of the flange.

6. A one-piece metallic car end, having side flanges and a top flange, the top flange having end extensions projecting over the upper ends of the side flanges.

7. A one-piece metallic car end having side flanges and a top flange, the top flange having end extensions projecting over the upper ends of the side flanges, said side flanges having notches at their upper ends arranged beneath the extensions of the top flange.

8. A one-piece metallic car end including a web provided with top, bottom and side flanges, the top and bottom flanges projecting in opposite directions, one of the last mentioned flanges being integral with certain ends of the side flanges.

9. A one-piece metallic car end including a web provided with top, bottom and side flanges, the top and bottom flanges projecting in opposite directions, one of the last mentioned flanges being integral with certain ends of the side flanges, said top flange having a depending reinforcing apron.

10. A one-piece metallic car end, including a web provided with top, bottom and side flanges, the top and bottom flanges projecting in opposite directions, and an intermediate reinforcing shelf arranged between the top and bottom edges of the web, and projecting from the web.

11. A one-piece metallic car end, including a web provided with top, bottom and side flanges, the top and bottom flanges projecting in opposite directions, and an intermediate reinforcing shelf arranged between the top and bottom edges of the web, and projecting from the web, said shelf having a depending reinforcing apron.

12. A one-piece reinforced metallic car end, including a substantially rectangular web provided at its lower corners with depending extensions, and an angular flange reinforcing

- each of said extensions, and merging at its upper end into a reinforcement of the web.
13. A one-piece metallic car end including a web provided with a top flange and an intermediate shelf, stake pockets provided in the flange, said shelf being positioned beneath said pockets to support stakes inserted in the pockets. 70
14. A one-piece metallic car end including a web provided with a top flange and an intermediate shelf, stake pockets provided in the flange, said shelf being positioned beneath said pockets to support stakes inserted in the pockets, and lugs on the shelf for retaining stakes in position. 75
15. A one-piece metallic car end including a web provided with a top flange and an intermediate shelf, stake pockets provided in the flange, said shelf being positioned beneath said pockets to support stakes inserted in the pockets, and reinforced lugs arranged on the shelf and cooperating with the pockets to retain stakes in position. 80
16. A one-piece metallic car end, including a web provided with a top flange and an intermediate shelf, stake pockets provided in the flange, said shelf being positioned beneath said pockets to support stakes inserted in the pockets, said flange being widened at the places where the pockets are located. 85
17. A one-piece metallic car end, including a web provided with a top flange and an intermediate shelf, stake pockets provided in the flange, said shelf being positioned beneath said pockets to support stakes inserted in the pockets, each of said pockets having a reinforcing bead at its lower end, the ends of the bead merging into the web. 90
18. A one-piece metallic car end including a substantially rectangular web provided with a top flange having a reinforcing apron at its outer edge, walls joining the web and apron and spaced apart to provide stake pockets at the upper end of the web. 95
19. In a metallic car end, means for mounting a valve on the exterior thereof, said means including bolt receiving apertures, and an accessible recess permitting said bolts to be attached or removed from the exterior of the car end. 100
20. A metallic car end including a part having bolt receiving slots, a portion of the car end being recessed to permit the passage of bolts through said slots and said bolts to be attached or removed exteriorly from said part of the car end. 105
21. In a one-piece metallic car end, a substantially rectangular web provided with integral pockets forming ladder steps, said steps projecting exteriorly of the car end only. 110
22. A one-piece metallic car end including a substantially rectangular web having lower depending corner extensions provided with integral push pole receiving pockets. 115
23. A one-piece metallic car end including a substantially rectangular web, edge flanges reinforcing the sides and bottom of said web, and push pole receiving pockets integral with the lower corners of the web and reinforced by said flanges, said pockets being positioned below the bottom one of said flanges. 120
24. A metallic car end having lower depending corner extensions provided with reinforced pull chain apertures. 125
25. A one-piece metallic car end including a substantially rectangular web provided with side and bottom flanges, extensions depending from the lower corners of the web, flanges extending along the side edges of the extensions and merging into the side flanges of the web, and jacking pads at the lower ends of the extensions, merging into the flanges of the extensions. 130
26. A one-piece metallic car end of the vertical type provided with an integral upstanding gable extension and a substantially horizontal reinforcing flange having stake pockets therein. 135
27. A one-piece metallic car end of the vertical type, including a substantially rectangular web and a substantially horizontal flange, continuations of said web forming an upstanding gable extension of increasing height from its ends towards its central portion. 140
28. A one-piece metallic car end of the vertical type provided with an integral upstanding gable extension, said extension being of increasing height from its ends toward its central portion, said car end also having an integral substantially horizontal flange at the base of the gable. 145
29. A one-piece metallic car end of the vertical type provided with an integral upstanding gable extension having reinforcing ribs extending upwardly from the main portion of the car end. 150
30. A one-piece metallic car end of the vertical type provided with an integral upstanding gable extension provided on one face thereof with integral reinforcing ribs which extend upwardly from the main portion of the car end. 155
31. A one-piece metallic car end of the vertical type provided with an upstanding gable extension and a substantially horizontal reinforcing flange, the gable extension having reinforcing ribs extending upwardly from said flange, certain of said ribs diverging upwardly and being of increased width toward their lower ends. 160
32. A one-piece metallic car end of the vertical type provided with an upstanding gable extension which is integral with the car end and provided at its upper edge with a reinforcing bead having a fillet on its lower side of relatively large radius for the purpose described. 165
33. A one-piece metallic car end provided with a substantially horizontally disposed re- 170

inforcing flange having stake pockets therein, and an upstanding integral gable extension projecting upwardly beyond said flange, and reinforcing ribs for the extension, integral 5 with the latter and forming continuations of the walls of the stake pockets.

34. A metallic car end including a web provided with a reinforcing flange, a chain pull loop integral with the web, and a reinforcing 10 rib arranged in alignment with the loop and integral with the web and flange.

35. A one-piece metallic car end including a web provided with a top flange and stake pockets in said flange.

16. In testimony whereof, we have signed this specification.

GEORGE A. SPILLER.
GEORGE T. JOHNSON.
